(57) **CLAIM**

The ornamental design for a body pillow, as shown and described.

DESCRIPTION

FIG. 1 is a top view of the body pillow;

FIG. 2 is a perspective, back view of the body pillow;

FIG. 3 is a back view of the body pillow;

FIG. 4 is a right view of the body pillow with the side arm and leg pillows extended for use;

FIG. 5 is a left view of the body pillow with the side arm and leg pillows extended for use;

FIG. 6 is a front view the body pillow;

FIG. 7 is a top view of the body pillow with the arm and leg pillows of one side wrapped over and around the head pillow;

FIG. 8 is a top view of the body pillow with the arm and leg pillows of both sides wrapped over and around the head pillow; and,

FIG. 9 is a bottom view of the body pillow.

The broken lines are illustrative of environmental structure only and form no part of the claimed design.

1 Claim, 4 Drawing Sheets
